UNITED STATES PATENT OFFICE.

ISAAC H. MILLIKEN, OF ASPINWALL, AND WILLIAM J. REGAN, OF PITTSBURGH, PENNSYLVANIA, ASSIGNEES TO THE MC CONWAY & TORLEY COMPANY, OF PITTSBURGH, PENNSYLVANIA, A CORPORATION OF PENNSYLVANIA.

UNCOUPLING MECHANISM.

1,417,546.

Specification of Letters Patent. Patented May 30, 1922.

Application filed October 6, 1921. Serial No. 505,693.

To all whom it may concern:

Be it known that we, ISAAC H. MILLIKEN and WILLIAM J. REGAN, citizens of the United States, residing respectively at Aspinwall, in the county of Allegheny and State of Pennsylvania, and Pittsburgh, in the county of Allegheny and State of Pennsylvania, have invented certain new and useful Improvements in Uncoupling Mechanism; and we do hereby declare the following to be a full, clear, and exact description of the invention, such as will enable others skilled in the art to which it appertains to make and use the same.

15 Our invention relates to uncoupling mechanism for actuating the lock of a car coupler to cause it to perform an unlocking operation. While the invention is intended to provide means well suited for use with the 20 Master Car Builders' standard D-type coupler, it is to be understood that mechanism embodying the invention may be applied to other types of couplers as well.

The principal object of the invention is to 25 provide an easily operated uncoupling mechanism consisting of a few simple and compactly arranged parts which may be readily assembled and disassociated and which when in assembled relation are interlockingly connected.

30 The primary feature of the invention, generally stated, consists in actuating the lock of a car coupler by means of a rotatable member supported rearwardly of said lock by pivotally connected members one of which is provided with spaced antifriction rollers between which the rotatable member extends, the member bearing the rollers being adapted to cause the rotatable member to per-

40 form an unlocking movement.

A further feature of the invention consists 45 in actuating the lock of a car coupler by a rotatable member which is supported rearwardly of the said lock by pivotally connected members one of which is adapted to have a swiveling movement with respect to the car.

50 There are other features of invention, residing in particular combinations of parts and in details of elemental construction, as will hereinafter appear.

In the drawings illustrating the preferred

embodiment of the invention, the scope whereof is pointed out in the claims—

Figure 1 is a view, partly in side elevation and partly in vertical section, of an uncoupling mechanism embodying the invention, the coupler shown being the well known Master Car Builders' standard D-type.

Figure 2 is a view, partly in side elevation and partly in vertical section, of a portion of the construction shown in Fig. 1, the parts being in the positions they occupy when the coupler lock has performed an extended unlocking movement.

Figure 3 is a detail sectional view on the line 3—3, Fig. 1, portions of the coupler, the coupler carrier iron and the uncoupling levers being broken away.

Figure 4 is a detail sectional view on the line 4—4, Fig. 1, portions of the uncoupling levers being broken away.

The coupler 1 is of the Master Car Builders' D-type. Its lock 2 is movably connected in the usual manner to a link 3 which projects downwardly through the lower side of the coupler head and is pivotally attached to a lock lift lever 4 that is itself pivotally connected to the under side of the coupler. The link 3 and pivoted lift lever 4 are, as shown in the drawings, preferably constructed and arranged in accordance with the standard practice of bottom lock lift devices of the D-type coupler. If the coupler is designed to have an extended range of lateral swinging movement it may be formed near the rear end of its shank with a pivot pin opening 5 for receiving a tail pin (not shown) whereby it may be pivotally connected to the draft rigging in a well known manner.

Operatively connected to the coupler lock 2 through the swinging lift lever 4 and link 3 is a vertically rotatable member 6 which is supported rearwardly of said lock by a swinging member 7 having journaled thereon a plurality of spaced antifriction rollers 8 between which the said member 6 extends. The rotatable member 6 normally rests upon the lower one of the rollers, both of which are adapted to engage the said member 6 to cause an unlocking rotation thereof when the trainman actuates the mechanism to unlock the coupler. By the use of the anti-

friction devices the rotatable member 6 may readily move lengthwise of the car not only during draft and buffing movements of the coupler but also as may be necessary to accommodate the member 6 to the pivotal movement of the lock lift lever 4. The rollers 8 may conveniently be journaled between the sides 9 of the swinging support 7 by means of rivets 10. The member 6 is preferably formed at its forward end with a hook 11 adapted to cooperate with the usual eye 12 at the rear end of the lift lever 4, such hook and eye connection resulting in causing the members 4 and 6 to be interlockingly connected in a manner preventing their accidental disassociation when the device is in service.

The member 7 carrying the rollers 8 is movably suspended from the coupler carrier iron 13 through the intervention of a member 14 having a swiveling connection with the coupler carrier iron, the connection between the members 7 and 14 being a pivotal one permitting the former to swing lengthwise of the car. A convenient mode of constructing the member 14 is to fashion its lower end with a hook 15 adapted to pass through an eye 16 on the carrier iron and to cooperate with a pivot bar 17 formed on said swinging member 7. The upper end of the member 14 may be conveniently formed with a coned head 18 which is of such size that it will not pass through the opening of the eye 16 on the carrier iron. By this means 35 the swinging member 7 and the swiveling member 14 are interlockingly maintained in assembled relation by means of a hook and eye connection, and the said swiveling member is permitted to have a universal rotary 40 movement with respect to the car. As the extent of swiveling of the member 14 upon its vertical axis is unlimited the side walls 9 of the swinging support may be placed closely adjacent the sides of the vertically 45 rotatable member 6, since the swiveling movement is ample to permit the member 6 to conform in angular position to all lateral swinging movements of the coupler 1.

The member 7 is adapted to be swung or 50 rotated upon the hook 15 to effect an unlocking rotation of the member 6 by means of a plurality of uncoupling levers 19 whose upwardly extending inner ends 20 are respectively adapted to be received in laterally 55 opening pockets or recesses 21 with which the swinging member 7 is provided on opposite sides of the rotatable member 6. For convenience of coring the recesses 21 may also be open at their upper ends. The uncoupling levers 19 extend towards the sides 60 of the car and preferably are of the well known form illustrated in the I. H. Milliken Patent No. 1,184,116, dated May 23, 1916.

In assembling the mechanism the hook 15 65 of the swiveling member 14 is first threaded

through the eye 16 of the carrier iron and brought to its ordinary position. The swinging actuating member 7 bearing the anti-friction rollers is then operatively associated with the hook of the swiveling member 14 70 and the rear end of the vertically rotatable member 6 is slid between the rollers 8. The hook 11 at the forward end of the member 6 is then hooked through the eye 12 of the lock lift lever 4, which latter is temporarily disconnected from the coupler head to permit this to be done, after which the inner ends 75 20 of the uncoupling levers 19 are inserted in their respective recesses 21 of the swinging actuating member 7 and the outer ends 80 of said levers are movably supported on brackets at the sides of the car in the usual way. As thus assembled the several parts of the mechanism are interlocked so that they may not become accidentally disassociated, it being necessary to withdraw the member 6 from the swinging member 7 before the latter may be removed from the hook 15 of the swiveling member 14.

When the trainman properly operates 90 either of the uncoupling levers 19 its upwardly extending inner end 20 presses rearwardly against the adjacent back wall of the member 7 causing its rollers 8 to engage opposite sides of the member 6 and induce 95 an upward rotation of the latter, thus actuating the lock lift lever 4 and link 3 and causing the coupler lock to perform an unlocking movement.

We claim:—

1. In an uncoupling mechanism, the combination with a car coupler and its lock, of means for moving said lock to unlocked position, said means involving a swinging member provided with a plurality of spaced 105 anti-friction rollers, means for movably supporting said swinging member, a rotatable member operatively connected to said lock and extending between said rollers, and means for actuating said swinging member 110 to cause said rotatable member to perform an unlocking movement.

2. In an uncoupling mechanism, the combination with a car coupler and its lock, of means for moving said lock to unlocked position, said means involving a rotatable member operatively connected to said lock and extending rearwardly therefrom, pivotally connected members constituting means for supporting said rotatable member rearwardly of said lock, one of said pivotally connected members being provided with spaced anti-friction rollers between which said rotatable member extends, and means for actuating said member which is provided 120 with said anti-friction rollers.

3. In an uncoupling mechanism, the combination with a car coupler and its lock, of means for moving said lock to unlocked position, said means involving a rotatable 130

- member operatively connected to said lock and extending rearwardly therefrom, an uncoupling lever, and means for supporting said rotatable member rearwardly of said lock, said last named means being adapted to actuate said rotatable member and including an anti-friction roller engaging said rotatable member and forming a support for one end of said uncoupling lever.
- 10 4. In an uncoupling mechanism, the combination with a car coupler and its lock, of means for moving said lock to unlocked position, said means involving a rotatable member operatively connected to said lock and extending rearwardly therefrom, pivotally connected members constituting means for supporting said rotatable member rearwardly of said lock, one of said pivotally connected members being adapted to have a 15 swiveling movement with respect to the car and one of said pivotally connected members being adapted to actuate said rotatable member, and an uncoupling lever for actuating said pivotally connected member last 20 named.
5. In an uncoupling mechanism, the combination with a car coupler and its lock, of means for moving said lock to unlocked position, said means involving a rotatable member operatively connected to said lock and extending rearwardly therefrom, pivotally connected members constituting means for supporting said rotatable member rearwardly of said lock, one of said pivotally 25 connected members being adapted to have a swiveling movement with respect to the car and one of said pivotally connected members being provided with a plurality of spaced anti-friction rollers between which 30 said rotatable member extends and by which the latter is engaged, and means for actuating said pivotally connected member last named to cause said rotatable member to perform an unlocking movement.
- 40 45 6. In an uncoupling mechanism, the combination with a car coupler, its lock and carrier iron, of means for moving said lock to unlocked position, said means involving a rotatable member operatively connected to said lock and extending rearwardly therefrom, pivotally connected members constituting means for supporting said rotatable member rearwardly of said lock, and an uncoupling lever for actuating one of said 50 pivotally connected members to effect an unlocking movement of said rotatable member, said pivotally connected members having a hook and eye connection, and one of said pivotally connected members having a 55 head whereby it is swivelingly connected to said carrier iron.
- 60 65 7. In an uncoupling mechanism, the combination with a car coupler, its lock and carrier iron, of means for moving said lock to unlocked position, said means involving
- a member swingingly connected to said coupler, a link operatively interposed between said swinging member and said lock, a rotatable member, pivotally connected members constituting means for supporting 70 said rotatable member rearwardly of said lock, and an uncoupling lever for actuating one of said pivotally connected members to cause said rotatable member to perform an unlocking movement, one of said pivotally 75 connected members being interlockingly connected to said carrier iron.
8. In an uncoupling mechanism, the combination with a car coupler and its lock, of means for moving said lock to unlocked 80 position, said means involving a rotatable member operatively connected to said lock, a plurality of pivotally connected members constituting means for supporting said rotatable member rearwardly of said lock, and 85 a plurality of uncoupling levers each of which is adapted to actuate one of said pivotally connected members to cause said rotatable member to perform an unlocking movement, said last named one of the pivotally 90 connected members being provided with spaced recesses disposed on opposite sides of said rotatable member and into which the respective uncoupling levers extend.
9. In an uncoupling mechanism, the combination with a car coupler and its lock, of means for moving said lock to unlocked position, said means involving a member swingingly connected to said coupler, a link movably connecting said swinging member 95 to said lock, a vertically rotatable member movably connected to said swinging member, a plurality of pivotally connected members movably connected to the car and constituting means for supporting said rotatable member rearwardly of said lock, one of said 100 pivotally connected members being provided with spaced anti-friction rollers between which said rotatable member extends, and means for actuating the said member 105 provided with rollers to cause said rotatable member to perform an unlocking movement.
10. In an uncoupling mechanism, the combination with a car coupler, its lock and carrier iron, of means for moving said lock to 110 unlocked position, said means involving a member swingingly connected to said coupler, a link operatively connecting said swinging member to said lock, a rotatable member movably connected to said swinging member, movably connected members constituting means for supporting said rotatable member rearwardly of said lock, and means for actuating one of said 115 movably connected members to cause said rotatable member to perform an unlocking movement, one of said 120 movably connected members being attached to said carrier iron through means permitting it to have a universal rotary movement with respect to the car.
- 125 130

11. In an uncoupling mechanism, the combination with a car coupler and its lock, of means for moving said lock to unlocked position, said means involving a rotatable member operatively connected to said lock, and a plurality of movably connected members movable with respect to the car for supporting said rotatable member rearwardly

of said lock, said rotatable member when in assembled position operating to retain said movably connected members in assembled relation.

In testimony whereof we affix our signatures.

ISAAC H. MILLIKEN.
WILLIAM J. REGAN.
